UMBRELLA CONSTRUCTION

David M. Cohen, New York, N. Y., assignor to
George B. Cohen, Long Beach, N. Y.

Application July 21, 1949, Serial No. 105,927

8 Claims. (Cl. 135—36)

1

This invention relates to an improved umbrella construction, and its object is to provide a simple and inexpensive arrangement for interconnecting the ferrule of an umbrella and the fabric of its cover.

In the construction of umbrellas in common use the ferrules are attached to the ends of the shanks and are easily displaced and lost. According to my invention the ferrule is permanently affixed to the fabric and the foregoing difficulty is overcome. Further objects are to simplify the operation of assembling parts of an umbrella and to provide a leak-proof connection between the ferrule and the fabric cover.

These and other objects of the invention will appear in the following specification, in which I will describe some structures in which it is embodied, and point out its novel features in claims.

This application is a continuation-in-part of my application Serial No. 675,918, filed June 11, 1946, since abandoned.

Referring to the drawings—

Fig. 1 is a sectional elevation of a part of an umbrella which is made according to and embodies my invention;

Fig. 2 is an inverted plan view of the parts shown in Fig. 1, taken from the line 2—2 of Fig. 1; and

Fig. 3 is a sectional elevation of a portion of two of the parts shown in Fig. 1, showing them in full lines in their position before being clamped to the fabric of an umbrella, and illustrating in dotted lines their clamping position.

A modified construction is shown in Figs. 4 and 5, of which Fig. 4 is a sectional elevation and Fig. 5 a perspective view of two of the parts separated from each other.

A simple modification which I now consider the preferred form of my invention is shown in Fig. 6, which is a sectional elevation, with the parts assembled on the shank of an umbrella.

10 designates a metallic ferrule, in the upper portion of which a cylindrical pocket 11 is formed. 12 is a cylindrical portion of larger diameter below the pocket 11, and 13 is an annular shoulder between the pocket 11 and the portion 12. At the lower end of the portion 12 the metal is bent outwardly to form a flange 14.

20 is a grommet member which, as shown in Fig. 3, has a cylindrical body portion 21 with an outwardly projecting flange 22 at one end. The inner diameter of its cylindrical portion corresponds to that of the portion 12 of the ferrule. Its flange 22 lies against the flange 14 of the ferrule, the outer edge of which is bent over and under the flange 22, as shown at 15, to fasten the parts together. The lower end of the body 21 may be notched, as shown at 23 (Figs. 2 and 3).

30 is a washer. In assembling these parts a circular opening is formed in the umbrella fabric 31, and the fabric is folded around the washer in the manner shown in Fig. 1. Then the washer, with the fabric around it, is placed on the body portion 21 of the grommet and pushed up against the latter's flange 22. The outer diameter of the

2

washer is slightly less than the inner diameter of the bent-under edge 15 of the ferrule, so that the fabric is pinched between these parts.

The lower part of the body 21 of the grommet is then bent outwardly and forced up against the part of the fabric which lies under the washer, with its outer edge bent upwardly, as shown at 24 in Fig. 1, to pinch two layers of the fabric between this outer edge of the grommet and the adjacent edge of the flange of the ferrule. Thus, an absolutely water-tight connection is made between the fabric and the ferrule.

The shank 40 of the umbrella has a portion 41 which fits into the body portion 21 of the grommet and into the portion 12 of the ferrule, and a part 42 of smaller diameter which fits into the pocket 11. A shoulder is formed between these parts 41 and 42 of the shank, which abuts the shoulder 13 in the ferrule.

It is not necessary to cement the ferrule onto the shank; in fact, it is sometimes desirable to have it removable. By this construction the ferrule is permanently affixed to the umbrella fabric so that it cannot be displaced and lost.

25 In order to adapt this invention to ferrules made of plastic or other molded materials, a construction like that shown in Figs. 4 and 5 may be used. In these figures the ferrule is designated by a reference numeral 10A. Its inner contour is like that shown in the preceding figures, except that of its flange 14A. This flange has a downwardly projecting rim having an inner cylindrical surface 16, from the lower part of which angularly spaced ears 17 project inwardly. In this case the body portion 21 of the grommet member 20A is the same as that shown in the previously described construction, but its flange 22A is provided with angularly spaced indentations 25, which correspond in size and in position to the ears 17 of the ferrule. If desired, an arcuate slot 26 may be provided in the flange, and a pin 18 in the ferrule to fit it.

45 The grommet is attached to the ferrule by inserting it with the indentations 25 angularly aligned with the ears 17 and giving it a partial rotation to bring the non-indented parts of the flange 22A back of the ears 17. If the slot 26 and pin 18 are provided, the degree of this rotation is limited by them. The fabric 31 is affixed to the grommet in the manner described previously.

50 The ferrule 10B in Fig. 6 may be made of plastic or other desired material. It has a central opening 12A and an integral outwardly extending flange 14B at its lower end.

A flange 22B, which extends outwardly from the upper end of the cylindrical body 21A of the grommet member 20B, abuts the flange 14B of the ferrule. This flange extends up around the outer edge of the flange 14B as at 27 and over its top as at 28. Then, after the washer 30, with the fabric 31 of the umbrella folded over it, is placed around the body 21, the lower end 29 of the flange 65 is bent under it and pressed into engagement with

the fabric. A shank 40 is placed in the structure thus formed.

By the use of this invention the operation of assembly is expedited. The ferrule is irremovably applied to the fabric, and a leak-proof assembly is formed.

Various modifications in construction, mode of operation, method and use of an invention may and do occur to others, especially after benefiting from knowledge of such a disclosure as that herein presented, of the principles involved, but the invention itself is not confined to the present showing.

I claim:

1. An umbrella structure comprising a hollow ferrule of rigid material adapted to receive the shank of the umbrella and having an integral outwardly projecting flange at its lower end, a grommet member having an outwardly projecting flange at its upper end abutting and affixed to the ferrule flange, and a washer having the fabric of the umbrella folded around it with the fabric on the upper side of the washer in contact with the grommet flange, said grommet member having an outwardly extending lower portion 25 pressed into permanent engagement with the fabric on the under side of the washer.

2. An umbrella structure comprising a hollow ferrule of rigid material adapted to receive the shank of the umbrella and having an integral 30 outwardly projecting flange at its lower end, a grommet member having an outwardly projecting flange at its upper end abutting the ferrule flange, a part of one of said flanges extending around the outer edge of the other flange, and a washer 35 having the fabric of the umbrella folded around it with the fabric on the upper side of the washer in contact with the grommet flange, said grommet member having an outwardly extending lower portion pressed into permanent engagement with the fabric on the under side of the washer.

3. An umbrella structure comprising a hollow ferrule of rigid material adapted to receive the shank of the umbrella and having an integral outwardly projecting flange at its lower end, a grommet member having an outwardly projecting flange at its upper end abutting the ferrule flange, a part of the ferrule flange extending around the outer edge of the grommet flange, and a washer 40 having the fabric of the umbrella folded around it with the fabric on the upper side of the washer in contact with the grommet flange, said grommet member having an outwardly extending lower portion pressed into permanent engagement with the fabric on the under side of the washer.

4. An umbrella structure comprising a hollow ferrule of rigid material adapted to receive the shank of the umbrella and having an integral outwardly projecting flange at its lower end, a grommet member having an outwardly projecting flange at its upper end abutting the ferrule flange, a part of the ferrule flange extending around the outer edge of the grommet flange, and a washer having the fabric of the umbrella folded around it with the fabric on the upper side of the washer in contact with the grommet flange, said grommet member having an outwardly extending lower portion pressed into permanent engagement with the fabric on the under side of the washer, the outer edge of said portion being 70 turned upwardly to engage a part of the fabric between said upturned edge and the part of the ferrule flange under the grommet flange.

5. An umbrella structure comprising a hollow ferrule of rigid material having an opening in its

lower end, a grommet member affixed to the ferrule having an opening therein, a washer having the fabric of the umbrella folded over it with the fabric of the upper part of the washer in contact with the grommet member, an outwardly extending lower part of the grommet member being pressed into permanent engagement with the fabric on the under side of the washer, and a shank inserted in the openings in the ferrule and the grommet member.

6. An umbrella structure comprising a hollow ferrule of rigid material adapted to receive the shank of the umbrella and having an integral outwardly projecting flange at its lower end, a grommet member having an outwardly projecting flange at its upper end abutting the ferrule flange, a part of the grommet flange extending outwardly, around the outer edge of the ferrule flange and over the top of said ferrule flange, and a washer having the fabric of the umbrella folded around it with the fabric on the upper side of the washer in contact with the grommet flange, the lower part of the grommet member extending outwardly under the washer and pressed into permanent engagement with the fabric on the under side of the washer.

7. An umbrella structure comprising a hollow ferrule of rigid material adapted to receive the shank of the umbrella and having an opening therein, and an integral outwardly projecting flange at its lower end, a grommet member having an opening therein and an outwardly projecting flange at its upper end abutting the ferrule flange, a part of the grommet flange extending upwardly around the ferrule flange and inwardly over the ferrule flange, and a washer having the fabric of the umbrella folded around it with the fabric on the upper side of the washer in contact with the ferrule flange, the lower part of the grommet member extending outwardly under the washer and pressed upwardly into permanent engagement with the fabric on the washer to engage a part of the fabric between said upturned edge and the part of the ferrule flange under the grommet flange.

8. An umbrella structure comprising a hollow ferrule adapted to receive the shank of the umbrella having an integral outwardly projecting flange at its lower end, a grommet member having an outwardly projecting flange at its upper end abutting the ferrule flange, means for attaching the grommet member to the ferrule flange, said means comprising interlocking ears and indentations on said abutting flanges, and a washer having the fabric of the umbrella folded around it with the fabric on the upper side of the washer in contact with the grommet flange, said grommet member having an outwardly extending lower portion pressed into permanent engagement with the fabric on the under side of the washer.
